CARROTING AND DRYING OF FUR-BEARING ANIMAL SKINS

Robert E. Naumburg, West Englewood, N. J., assignor to Jonas & Naumburg Corporation, New York, N. Y., a corporation of New York

Application July 10, 1944, Serial No. 544,294

13 Claims. (Cl. 8—112)

1

This invention relates generally to the art of treating fur-bearing animal skins and more particularly to treating skins the fur of which is to be separated from the skin or pelt for subsequent use in making felted products.

In the manufacture of felted articles such as hats, fibres having felting properties are demanded in vast quantities. For the most part the source of the fibres, as is well known, is fur-bearing animals; rabbit fur being most commonly used, although other furs are suitable for the purpose. Rabbit fur, by reason of relative cost, is more extensively used than any other for making felt hats.

The raw or untreated fur in its natural state is considered unsuitable for hat making because the fibres lack the desired property of felting. To impart thereto the necessary felting properties it is customary in the art to treat the fur while still attached to the pelt with a carotting solution after which the fur-bearing skins are subjected to a conditioning treatment involving the drying of the carotted skins. Thereafter, the fur is removed from the pelt. As a result of the carotting and other treatment incidental thereto, there is imparted felting properties to the fur fibres.

In the various treatments to which the skins are subjected from the raw state through the stage when the fur is finally conditioned for making felted products such as hats, the skins are wetted or moistened. If wetted before the application of the carot, the skins are normally dried prior to application of the carotting solution. Of course, the application of the carotting solution to the fur wets it to a greater or less extent. It has been the practice to subject the skins to a drying treatment after application of the carotting solution prior to removal of the carotted fur from the pelt. Accordingly, whether carried out before or after the carotting solution is applied to the fur the drying procedure is an important part or parts of the process of producing fur fibres having the desired felting characteristics.

Heretofore it was not uncommon practice when treating skins with a mercury carot to dry the skins in trays in a chamber heated by steam pipes to about 260° F. The necessary drying could be done in about fifteen to twenty minutes but the skins were rendered "yellow." The resulting coloration of the carotted fur made it undesirable for use in producing hats of light shade.

Those skilled in the art will understand, of

course, that there are different kinds of carotting solutions and regardless of the type of solution used a treatment involving a drying operation is employed prior to removal of the fur from the pelts.

According to another method of drying heretofore employed the skins which have been treated with carotting solution (the so-called "white" carot) are dried by advancing them on trays through a tunnel where the temperature advances in stages from about 120° to about 150° F. while circulating hot air through the trays. This method of drying ordinarily requires about ninety to one hundred minutes. Furthermore, this method depends primarily upon convected heat.

There are other methods employing convected heat in which the temperature of the drying chamber is maintained below 100° F. but of course this requires much longer; twenty-four to forty-eight hours being not common.

The object of the present invention is to provide a different, and more rapid method of drying fur-bearing animal skins of the type above mentioned and also apparatus in which the method may be carried out.

The invention provides a method whereby wetted or otherwise moistened fur-bearing skins are subjected to infra-red rays or radiant energy in the presence of an atmosphere maintained in turbulent state over and in contact with the skins.

According to a preferred method of practicing the invention, carotted skins to be dried are passed through a zone in which they are exposed to infra-red rays or radiant heat while simultaneously passing a current of air at high velocity over and in contact with the skins, the intensity of the radiant energy being sufficient to cause singeing or burning of the fur but for the effect of the moving current of air over the skins.

In addition to the fur drying procedure just mentioned, the invention comprehends the preparation of fur having felting properties by a method which comprises applying a carotting solution to the fur-bearing skins and substantially immediately thereafter without intermediate conditioning, treating the skins in accordance with the above mentioned radiant heat drying procedure, after which the fur may, if desired, be immediately removed from the pelt by the usual cutting machines without the necessity of any additional intermediate conditioning after the drying operation.

The apparatus which is described in further

detail hereinafter and which I prefer to use in practicing the process of the invention on a commercial scale comprises, in general, (1) a heating chamber wherein is maintained a concentrated zone of radiant heat through which the skins to be dried are passed in such manner that the infra-red rays strike the surfaces of the skins, (2) an elongate auxiliary drying tunnel communicating with the heating chamber through which the skins are passed after being subjected to the radiant heat rays, (3) means for maintaining the atmosphere adjacent the skins in a state of turbulence while they are in the path of the radiant heat rays, such means being preferably an air blower capable of causing a large volume of air to pass at high velocity over and in contact with the skins as they are caused to travel through the heating chamber and its associated tunnel, and (4) means for carrying the skins to be treated through the heating chamber and tunnel, such means being preferably a pair of endless flat mesh conveyors arranged with their upper and lower runs respectively passing through the chamber and tunnel in adjacent spaced parallel relationship between which the skins may be held without undue displacement as they are carried through the heating chamber and tunnel.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part hereof, in which,

Fig. 1 is a side view in elevation of apparatus in which the method of the invention may be practised. The view is partly diagrammatic and also partly broken away;

Fig. 2 is a vertical side view in section to larger scale through the heating chamber on line 2—2 of Fig. 3;

Fig. 3 is a view on line 3—3 of Fig. 2;

Fig. 4 is a side view to larger scale of a brush ing device, comprising a rotary brush and associated guides; and

Fig. 5 is a plan view showing the guides.

Referring to the drawings, in which like reference characters denote similar parts, the heating chamber, and its associated tunnel, designated generally by reference characters 10 and 11, respectively, are mounted on suitable supporting or frame members 12. Both the chamber and tunnel are constructed of heavy sheet metal which is preferably heat insulated. Any suitable insulation means may be employed; asbestos-cement 13 being shown in the drawings.

An air duct 14 from an air blower 15 leads into the interior 16 of the heating chamber, the entering air port 17 extending across substantially the entire width of the heating chamber. The air blower 15 takes suction through a conduit 18 through an air filter 19 as it is desirable to employ clean air. The blower 15 may be driven by a motor 15a or other suitable prime mover and should be capable of imparting a high velocity head to the air discharged from the duct 14. A chimney 20 connected to the tunnel 11 near its discharge end is provided to carry away the air passed into the tunnel together with vapor or fumes which it picks up from the skins being treated. An exhaust fan 20a is mounted within

the chimney to aid in exhausting the air and fumes.

To convey the skins to be treated through the heating chamber and the tunnel, a pair of metal endless open mesh flat conveyor belts are provided. An upper conveyor belt 21 is trained over rollers 22 and a driven roller 23 and a lower conveyor belt 24 is trained over rollers 25, 26 and driven roller 27. It will be apparent that a sufficient number of rollers will be employed and spaced along the runs of the belts to avoid sagging and such rollers may be mounted on suitable supports on the frame such as those indicated by the reference characters 28 and 29 in Fig. 2 and Fig. 3. The rollers may be provided with sprocket gears 30 (see Fig. 3) to engage sprocket chains 31 which are fixed to the edges of the conveyor belts.

It will be observed the upper run 32 of lower conveyor belt 24 extends beyond the upper conveyor belt at the head end of the machine thus providing a moving feeder platform 33 upon which skins to be treated (designated by reference character 50) may be suitably placed and spaced. At the discharge end of the machine the lower run of the upper conveyor belt extends beyond the lower conveyor belt to accommodate the rotary brush 34 described in further detail hereinafter.

It will be further observed the lower run 35 of the upper conveyor belt 21 and the upper run 32 of the lower conveyor belt 24 are maintained in adjacent spaced relationship as they pass through the heating chamber and tunnel of the machine.

The two belts are caused to travel at the same lineal speed. This is accomplished by gearing the roller 23 to the driven roller 26 the latter being driven by a sprocket chain 36 trained over sprockets mounted on the rollers 26 and 27. Roller 27 is driven by a sprocket chain 37 trained over sprockets on the roller 27 and the driven shaft 38 of variable-speed speed reducer 39. The speed reducer which may be of known type is driven by a prime mover (not shown). Consequently,

means are provided to drive the conveyor at any adjusted speed desired and the arrangement of the conveyor belts is such that skins placed upon the travelling feeding platform 33 enter the bight of the conveyor belts and by reason of the skins then being between the two belts they are, in effect, clamped and held firmly in flat condition as they pass through the heating chamber and tunnel. It is to be understood, of course, the conveyor belts should be of open mesh type to expose as much as possible of the surfaces of the skins.

The heating chamber is designed to provide a zone of radiant heat and so fashioned that the infra-red rays are projected upon the surfaces of the skins as they are passed through the chamber.

Although various means may be used to produce radiant heat, in my preferred arrangement there are provided a plurality of gas burners 40 extending across the width of the interior 16 of the heating chamber. It will be observed, as shown in the drawings, four such burners are disposed in the bottom wall and one such burner in the top wall of the chamber. However, a different number may be employed both top and bottom, the important consideration being to provide ample infra-red rays or radiant energy directed upon the surfaces of the skins to accomplish the desired amount of heating.

Each burner 40 is equipped with an individual shut-off valve 41 which is connected by a nipple 42

to its respective burner. Each burner is also provided with a mixer valve 43. The mixer valves are connected to a gas manifold 44 supplied with gas from a suitable source (not shown) by nipples 45 and to an air manifold 50a by nipples 46 equipped with regulator valves 47. Filtered air is supplied to the manifold 50a by an air blower 48 taking suction through a filter 49. This air blower is driven by a suitable prime mover, such as a motor 48a.

The bottom wall of the heating chamber (see Fig. 2) is provided with refractory members 51 which are constructed of ceramic material. The spaces between the refractory members 51 and the burners are filled by filler members 51a whose surfaces may be of metallic or other material having good reflector qualities. It will be noted, the burner ports 52 direct the combustion mixture against the upwardly curved surfaces of the troughs 53 provided by the burners and ceramic elements 51 as indicated at 54. The ceramic elements 51 may thus be heated to incandescence. Like burners are likewise disposed in the upper wall. The arrangement provides a substantial quantity of radiant heat concentrated in the heating chamber and the infra-red rays are directed into the path of travel of the skins 50.

Each burner 46 is provided with a pilot burner 55 controlled by a valve 56. The pilots are connected to a manifold 57 supplied with gas from suitable source (not shown). The tip ends of the pilot burners are protected from the air blast through the heating chamber by pilot baffles 58. By maintaining a pilot light at each gas burner the various burners may be turned on or off as desired without opening up the heating chamber. However the heating chamber 10 is provided with an insulated hinged door 59 at either side. The doors are provided with windows 60 for convenience in observing the interior of the chamber.

At the discharge end of the tunnel 11 there is provided a rotary cylindrical brush 34 which may be mounted on suitable supports and driven in the direction of arrow 34a by a prime mover (not shown). The brush is provided at its periphery with relatively stiff but flexible bristles 61, the outer ends of which contact the fur of the skins when they are passed through the machine fur side down. Cooperating with the brush and conveyor belts are guides 62 and 63, shown more clearly in Figs. 4 and 5. The guides comprise flat plates shaped preferably as shown in Fig. 4 and Fig. 5, mounted on shaft supports 64. The guides are positioned and fixed so that their upper edges serve to clamp the skins discharged from the pair of conveyor belts but permit the upper run 35 to carry them forward into contact with the bristles 61 of the rotating brush and finally over the guide 63 from which they are delivered to chute 65. The skins may be discharged from the chute into a suitable collecting bin or otherwise handled. While the rotary brush may, in some instances, be dispensed with, it is useful to brush out the fur on the treated skins to separate the fibres and to remove "dags," if present.

The machine which has been described, may be hand-fed and may be used for drying raw uncarroted skins but it is particularly adapted for treating skins which have been carotted. Moreover, the machine lends itself admirably to a system of carroting and drying without time consuming intermediate conditioning, and its use results in saving in labor and floor space.

According to the invention there is provided a 75

machine adapted for carroting and drying in a continuous operation. The carroting step may be carried out on that part of the machine shown more or less conventionally in Fig. 1 and designated by reference character 70. In general, this part of the machine comprises a feeding platform 71, an endless flat rubber conveyor belt 72, to carry skins to be carroted past the rotating brush 73 which picks up carroting solution from 10 a bath 74 of the solution in tank 75. Additional brushes 76 and guides 77, such as those shown in Fig. 4 are provided for brushing the solution into the fur as the skins pass, pelt side up, through the carroting machine. The skins with the solution well brushed into the fur are delivered on to the 15 moving platform 33 where they may be inspected, if desired, prior to being carried directly through the drying machine. While only one carrot applying roll 73 has been shown for illustrative purposes, two or more such applying rolls may be provided for the purpose of applying the carrot in divided portions. In my preferred practice, I prefer to apply the carroting solution in two or three portions, brushing it in well after each 20 application. This practice results in a saving in solution without sacrifice to effective chemical reaction brought about when drying the carroted skins according to the drying process of my invention.

30 While other apparatus for practising the method of my invention may be suggested by the disclosure herein the following is set forth as one manner of carrying out the process. And for purposes of illustration the process is described 35 in connection with the treatment of rabbit skins although other animal skins whose fur is used for producing fibres having felting properties may be treated in accordance with the invention.

It may be assumed the raw skins have been 40 dried preparatory to application of the carroting solution and such drying may be performed in the apparatus constructed according to the foregoing description. The carroting solution may be applied in any known manner either by hand or 45 machine brushing as mentioned hereinbefore. Any of the well known types of carroting solutions, of which there are a number available, may be employed. I preferably carrot the skins by machine.

50 Upon delivery of the skins from the carroting machine, the fur is wetted by the solution. Whereas, under prior practices, it is customary to "pile" the skins and allow a considerable time to elapse to permit of the desired chemical 55 action upon the fibres prior to drying, such delay incident to "piling" is not necessary when practising the method of my invention. According to my preferred practice the skins are delivered directly from the carroting step and dried immediately thereafter without the delays incident to intermediate conditioning.

The skins are fed to the feeding platform 33 of the drying machine fur side down. The skins 50 are clamped between the adjacent pair of parallel conveyor belts. They then pass fur side down into the interior 16 of the heating chamber 10 wherein the gas burners are in operation. A sufficient number being used to insure a sufficient amount of radiant heat for the quantity of skins passing through and the rate of speed of the conveyors. Air blower 15 supplies a continuous blast of air which is discharged from the port 17 into the heating chamber. The air enters the heating chamber as its head end.

As the infra-red rays strike the skins 50 and

importantly on the lower or fur side of the pelt, if carrottet, the radiant energy penetrates the fur and is absorbed and converted into heat while simultaneously the air blast striking the fur keeps the fur sufficiently cool to avoid singeing or burning. Moreover, the air current maintains a turbulence adjacent the skins which aids evaporation and tends to keep the individual fibres in a state of agitation whereby they are more effectively exposed to the heat rays when considered as individual fibres. This aids in accelerating chemical reaction of the carrot on the fibres. The skins then pass into the auxiliary drying tunnel 11 where the drying is continued while the air at high velocity travels over them in the same direction to carry away evaporated moisture and fumes and where the skins are progressively cooled prior to discharge from the tunnel. The air and fumes are continuously exhausted through the chimney 20 with the aid of the exhaust fan 20a. As the dried skins are discharged from tunnel 11 they are brushed on the fur side by the bristles 61 of rotating brush 34, this brushing serving to loosen and separate any clotted fibres or "dags." If desired, the skins may then be delivered directly to the cutting machines to remove the carrottet fur without intermediate conditioning, such as treatment in a piling room or conditioning room which has heretofore been common practice.

By way of example for illustrative purposes, I have treated skins with excellent results in the following manner. The rabbit skins after being dried were treated with a carrottet solution known in the trade as Beal McGregor carrot and immediately thereafter dried in a machine as illustrated in the drawings. The heating chamber and tunnel was approximately thirty inches wide and accommodated a conveyor belt twenty-eight inches wide. The heating chamber 16 was approximately twelve inches deep permitting of placing the burners 40 about five inches from the path of travel of the skins 50. The auxiliary tunnel 11 connected to the heating chamber was of the same width as the heating chamber and at its head end about the same depth of the heating chamber; the bottom wall of the tunnel being inclined upward for a short distance of about three feet and then the tunnel 11 throughout its twenty-foot length was reduced to about six inches in depth. The tunnel therefore was such as to insure a high velocity to the air passing through it, the linear velocity of the air greatly exceeding the rate of travel of the skins.

Air was delivered through air duct 14 into the heating chamber at approximately 6000 C. F. M. and the burners 40 were fired to maintain a temperature just beyond the discharge end of the heating chamber 16 at about 300° F., indicated by a thermometer T. The belt conveyors 21 and 24 were operated at a lineal speed which allowed the skins to pass the zone of radiant heat in the heating chamber in about twenty seconds and to pass through the tunnel 11 in about three minutes.

Of course these operating conditions may be varied within limits, but I prefer to limit the temperature at the discharge end of the heating chamber from 150° to 500° F., the time the skins are subjected to the infra-red rays from ten to thirty seconds, and the total drying time from one to six minutes. However, I do not wish to be understood as holding these times and temperatures must be adhered to under all sets of conditions because of variables introduced with kind

of skins, kind of carrot, strength of carrot, amount of carrot applied, speed of conveyor, moisture present and like considerations. With the teachings of the disclosure, it will be a matter of adjusting the operation of the machine to obtain the desired amount of drying when the skins are discharged from the auxiliary drying tunnel.

It will be seen from the foregoing description that my invention provides a rapid method of drying animal skins, the fur of which is treated to impart thereto felting properties. The drying is accomplished by subjecting the skins to infrared rays in a high temperature zone under conditions which accelerate the desired chemical reaction between carrottet solution and the fur fibres without singeing or burning. The drying treatment lends itself to a combined system of carrottet treatment and drying without intermediate conditioning and there is provided a brushing operation after drying, if such brushing is desired. The various features of the invention effect a saving of labor, time and floor space. Moreover, less carrottet solution may be used than in prior practices to produce the desired result. Consequently, there is less liquid to evaporate with less time required to evaporate it, as well as savings in chemicals. Moreover, fur from skins treated according to the invention produce carrottet fibres which have better felting properties which permits of producing stronger and better felt hats.

In accordance with a requirement of division by the Patent Office, a divisional application Serial No. 588,977, was filed April 18, 1945. Apparatus disclosed herein is claimed in said application.

While certain novel features of the invention have been disclosed herein, it will be understood that various omissions, substitutions and changes may be made by those skilled in the art without departing from the spirit and scope of the invention comprehended by the annexed claims.

What is claimed is:

1. In the art of preparing fur for felting, a method of treating fur-bearing animal skins from which said fur may be produced which comprises passing the fur-bearing skins which have been moistened by the application of carrottet solution thereto through a zone of radiant heat energy, wherein the radiant heat rays strike the fur, simultaneously passing air over said skins while said skins are passing through said zone whereby the atmosphere adjacent the fur is maintained in a state of turbulence, said radiant heat being of sufficient intensity to singe the fur if said atmosphere is maintained quiescent.

2. In the art of preparing fur for felting, a method of treating fur-bearing animal skins from which said fur may be produced which comprises applying carrot solution to the fur on said skins whereby to moisten the fur fibres with said solution, passing the skins through a zone of radiant heat rays while maintaining said skins in fixed spaced relationship and wherein the radiant heat rays strike the fur on the skins whereby the chemical reaction of the carrot solution upon the fur fibres is accelerated, simultaneously passing a current of air over and in contact with the fur whereby overheating of the fur fibres is inhibited, the intensity of said rays being sufficient to singe said fur in the absence of said air current.

3. In the art of preparing fur for felting, a method of treating fur-bearing animal skins from

which said fur may be produced which includes the steps of applying a carroting solution to the fur side of the skins, thereafter passing the carroted skins through a zone of radiant heat rays whereby the heat rays strike the fur on the skins and passing a current of air over and in contact with the fur, the intensity of said rays being sufficient to singe said fur in the absence of said air current and said air current being sufficiently strong to prevent singeing of the fur.

4. A method of treating fur-bearing animal skins which comprises applying a carroting solution to the fur on the skins and thereafter subjecting the skins to the action of radiant heat energy whereby the infra-red rays of the radiant heat energy strike the fur and the fur fibres absorb heat from said rays to accelerate the chemical reaction of the carrot upon said fibres and to effect evaporation of liquid from said applied solution and passing a current of air simultaneously over and adjacent said fur whereby to accelerate the evaporation and prevent the fur from becoming singed, said radiant heat energy being of sufficient intensity to singe the fur fibres when the adjacent air is maintained quiescent.

5. A method of treating and drying fur-bearing animal skins which comprises applying carroting solution to the fur on said skins, thereafter passing said skins through a first zone wherein is maintained a source of intense radiant heat energy the infra-red rays of which directly strike the fur on said skins whereby the skins are heated and chemical reaction of the carroting solution on the fur fibres and evaporation of said solution are accelerated, simultaneously passing a current of air over said skins in said zone in the direction of travel of said skins whereby the air is heated to a temperature within the range of 150° F. to 500° F., then passing said skins through a second zone wherein the drying is continued by passing the air over the fur of said skins in the same direction whereby fumes and moisture evaporated from said skins are carried away.

6. A method of treating fur-bearing animal skins which comprises applying carroting solution to the fur on said skins, then passing said skins through a first zone wherein is maintained a source of intense radiant heat energy so that the infra-red rays of the radiant energy directly strike the fur on said skins, simultaneously passing a current of air over said skins in said zone in the direction of travel of said skins whereby the current of air is heated to a temperature within the range of 150° F. to 500° F., then passing said skins through a second zone wherein said current of air is passed over the fur of said skins in the same direction at a velocity greater than the speed of movement of said skins and maintaining said skins in fixed spaced relationship while passing through said zones.

7. A method of treating fur-bearing animal skins which comprises applying carroting solution to the fur on said skins, thereafter passing said skins through a first zone wherein is maintained a source of intense radiant heat energy whereby the infra-red rays of the radiant heat energy directly strike the fur on said skins, simultaneously passing a current of air over said skins in said zone in the direction of travel of said skins whereby the temperature of said air increases while in said zone to a temperature within the range of 150° F. to 500° F. then passing said skins through a second zone wherein the temperature

is reduced and said current of air is caused to pass over the fur of said skins at a velocity greater than the speed of movement of said air while in the first zone.

5. 8. A method of treating fur-bearing animal skins which comprises applying carroting solution to the fur on said skins, thereafter passing said skins through a first zone wherein is maintained a source of intense radiant heat energy having 10 infra-red rays directly striking the fur on said skins whereby the skins are heated and chemical action of the carroting solution is accelerated, simultaneously passing a current of air over said skins in said zone in the direction of travel of said skins where 15 by the temperature of said air is raised to between 150° F. and 500° F., then passing said skins through a second zone wherein the temperature of the heated skins is gradually reduced and the air is passed over the fur of said skins at a velocity greater than the speed of movement of said skins.

9. A method of treating fur-bearing animal skins which comprises applying carroting solution to the fur on said skins whereby to moisten the fur with said solution, thereafter passing the skins through a first zone wherein is maintained a source of radiant heat energy, passing said skins through said zone wherein the skins are struck by the infra-red rays of said radiant heat energy, simultaneously passing a current of air through said zone over said skins whereby said air is heated to a temperature within the range of about 150° F. to about 500° F., and thereafter passing said skins through a second zone wherein 35 said current of air flows past said skins and is gradually reduced in temperature and continuing the movement of said skins in said current of air for a period sufficient to dry said skins.

10. A method of treating fur-bearing animal skins which comprises applying a carroting solution to the fur of said skins whereby to moisten them with said solution, thereafter passing the skins through a zone wherein is maintained a source of radiant heat energy, passing said skins 45 through said zone wherein the skins are struck by the infra-red rays of said radiant heat energy, simultaneously passing a current of air through said zone whereby said air is heated to a temperature above 300° F. but not substantially above 500° F., and thereafter passing said skins through a second zone wherein said current of air is passed over said skins and the temperature of said air in its course of travel is gradually reduced and continuing the movement of said skins in 55 the current of air for a period sufficient to dry said skins.

11. A process of treating fur-bearing animal skins which comprises carroting the skins by passing the skins through a carroting zone where 60 carroting solution is applied to the fur fibres of the skins and then passing the skins without substantial interruption of their movement through a drying zone wherein is maintained a source of radiant heat and the fur fibres of the skins are subjected to the infra-red rays of said heat, passing a current of air over and in contact with the fur while in said heated zone whereby said air is heated to a temperature within the range of 150° F. to 500° F. and continuing the movement 65 of the skins in the path of travel of the current of air whereby the skins are dried, said carroting and drying steps being effected in a single substantially uninterrupted pass of the skins through said zones.

75 12. In the art of producing fur for felting, a

method of treating fur-bearing animal skins preparatory to removal of the fur from the skins which comprises treating the fur on the skins with a solution of carotting agent in a carotting zone, thereafter passing said skins through a zone wherein is maintained a source of intense radiant heat the infra-red rays of which are directed onto the fur of the skins, passing a current of air over and in contact with said skins in the zone wherein is maintained the radiant heat whereby and wherein reaction of said solution on the fur fibres and evaporation of the solution is brought about and thereby drying the skins and brushing the dried fur on the skins to loosen dags, said carotting, drying and brushing being carried out mechanically in a single substantially uninterrupted pass of the skins through said zones, whereby the carotting, drying and brushing is performed as a continuous process without intermediate manual handling of the skins.

13. A method of treating fur-bearing animal skins which comprises applying carotting solution to the fur on said skins whereby the fur is moistened with said solution, thereafter and without substantial interruption of the movement of said skins, passing said skins through a first heated zone wherein is maintained a source of intense radiant heat energy having infra-red rays directed into the path of travel of said skins whereby the infra-red rays directly strike the fur on said skins thereby accelerating the reaction of said solution on the fur fibres, simultaneously passing a current of air over said skins in said zone whereby the temperature of said air increases to a temperature within the range of 150° F. to 500° F. and evaporation of said solution from the fur fibres is accelerated, then passing

said skins through a second zone wherein the temperature is reduced and continuing the movement of said skins without substantial interruption of their movement until dry whereby the skins are carotted and dried in a single substantially uninterrupted pass.

Patent No. 2,438,226.

March 23, 1948.

ROBERT E. NAUMBURG

It is hereby certified that errors appear in the printed specification of the above numbered patent requiring correction as follows: Column 2, line 21, for the word "common" read *uncommon*; column 6, line 74, for "as" after "chamber" read *at*; and that the said Letters Patent should be read with these corrections therein that the same may conform to the record of the case in the Patent Office.

Signed and sealed this 25th day of May, A. D. 1948.

[SEAL]

THOMAS F. MURPHY,
Assistant Commissioner of Patents.
